UNITED STATES PATENT OFFICE.

ALBERT A. ACKERMAN, OF CHICAGO, ILLINOIS, ASSIGNOR, BY MESNE ASSIGNMENTS, TO WARREN FEATHERBONE COMPANY OF MICHIGAN, OF THREE OAKS, MICHIGAN, A CORPORATION OF MICHIGAN.

STIFFENING-STRIP.

No. 902,194.

Specification of Letters Patent.

Patented Oct. 27, 1908.

Application filed September 4, 1903. Serial No. 171,943.

To all whom it may concern:

Be it known that I, ALBERT A. ACKERMAN, a citizen of the United States, residing in the city of Chicago, county of Cook, and State 5 of Illinois, have invented a new and useful Improvement in Stiffening-Strips, of which the following is a specification.

My invention relates to stiffening strips, such for example, as are used for dress and 10 corset stays, and the objects of my invention are: First: to produce a stiffening strip which shall be pliable in a direction across the strip. Second: to produce a strip which shall require a comparatively small 15 amount of thread for securing the individual cords together in the form of a flat strip, and third: to increase the unity of the strip by minimizing the danger of separation of the different cords when the outer threads 20 become accidentally broken at points here and there along the strip.

I attain my objects in the manner illustrated in the accompanying drawings, in which

25 Figure 1 represents a single bundle or cord of fibers. Fig. 2 represents a stiffening strip composed of three cords stitched together. Fig. 3 is a cross sectional view of the strip on a greatly enlarged scale, showing the manner of looping or interlocking the outer threads. Fig. 4 is a cross sectional view showing each stitch or bight of the outer thread inclosing two longitudinal cords. In Figs. 3 and 4 the outer threads 30 are shown in a loose condition for the purpose of illustrating the course of each thread in the preferred construction. Fig. 5 is a face view of the finished product upon a scale approximately natural size.

40 Similar letters refer to similar parts throughout the several views.

A single cord is shown in Fig. 1 and consists of a number of fibers *a* bundled together and permanently held by the wrapping 45 thread *b*. The said fibers *a* may consist of various substances, such as tampico, fibers of horn, or fibers of feathers cords and blades formed of the latter substance being commonly known as featherbone.

50 In the forming of a stiffening strip or blade according to my invention three or more cords constructed as above described are brought side by side and then stitched in a

zig-zag manner, as best shown in Fig. 2. In this zig-zag formation the stitch extends 55 obliquely from one edge of the strip to the other, and then returns obliquely across the strip, but always progresses along the strip in the same direction.

The form of stitch is best shown in Figs. 60 3 and 4 in which the upper thread *c* is engaged by the lower thread *d* by means of a looping or interlocking shown at *d*¹. It is desirable that the lower thread *d* in thus 65 engaging the upper thread *c* pass backward 70 upon itself in the manner shown, thereby making a true stitch. By this construction when the outer threads are drawn tight, as occurs in actual practice, there is a knotting 75 effect and the outer threads will be able to hold the cords *a* together even though said outer threads be broken in many places. This results in a distinct advantage over the form of stay where the outer threads are wound around the cords, for when wound, if 80 the thread breaks, it tends to greatly weaken the strip.

It will be understood that the stitching 85 may be single or multiple, that is to say, there may be two threads lying parallel 90 caught by one thread at the bottom, or caught by two threads at the bottom, but in either event there will be a single set of 95 stitches. The interlocking occurs at the edge of the strip as well as at the intervals intermediate of the edges thereof, and it is within 100 my contemplation that this interlocking may occur at points within the body of a cord itself as well as at points between two adjacent individual cords. It will be understood 105 that this zig-zag stitching takes the place of any wrapping or binding thread for securing the individual strands together, rendering such wrapping or binding unnecessary. If preferred, however, an additional binding or wrapping thread may be used. The 110 number of stitches in any straight stretch or reach of the zigzag stitching will depend of course upon the width in which the strip is manufactured; but it is essential that in 115 each of said straight stretches or reaches of the stitching there shall be a plurality of 120 stitches. That is to say, after each change of direction of the stitching to form the zig-zag effect there shall be a plurality of 125 stitches before the direction is again changed.

It will be obvious from an examination of the drawings and from the above description, that the strip produced by this manner of stitching will be flexible at the points where the outer threads interlock or engage each other, thereby greatly improving the quality and flexibility of the strip. Another advantage in this construction is that a comparatively small amount of exterior thread is required for securing the individual cords together.

In producing a strip for practical use, it is within my contemplation that the strip may be sized, calendered, or pressed and covered, as preferred by the manufacturer.

What I claim as new and desire to secure by Letters Patent is:

1. An article of the class described, comprising a plurality of continuous strands arranged side by side and stitching zig-zagged across all the strands, the threads of the stitching interlocking at a plurality of points in each reach of the zig-zagged stitching whereby the strands are all bound and secured together solely by said stitching into a flat resilient blade or tape.

2. An article of the class described, comprising a plurality of continuous resilient strands arranged side by side and a continuous zig-zagged row of stitches therethrough, each reach of said zig-zagged row of stitches being arranged to embrace all of the strands whereby they are all bound and secured together into a flat resilient blade or tape solely by said stitching, there being a plurality of stitches through said blade in each of the reaches, said strands consisting of fibered

quill portions of feather bound together by a wrapping thread.

3. An article of the class described, comprising a plurality of continuous resilient strands arranged side by side and a continuous zig-zagged row of stitches therethrough, each reach of zig-zagged row of stitches being arranged to embrace all of the strands whereby they are all bound and secured together into a flat resilient blade or tape solely by said stitching, there being a plurality of stitches through said blade in each of the reaches.

4. An article of the class described, comprising a plurality of continuous resilient strands arranged side by side and a continuous zig-zagged row of stitches therethrough, each reach of said zig-zagged row of stitches being arranged to embrace all of the strands whereby they are all bound and secured together into a flat resilient blade or tape solely by said stitching, the strands consisting of fibered quill portions of feather bound together by a wrapping thread.

5. An article of the class described, comprising a plurality of continuous resilient strands arranged side by side and a continuous zig-zagged row of stitches therethrough, each reach of said zig-zagged row of stitches being arranged to embrace all of the strands whereby they are all bound and secured together into a flat resilient blade or tape solely by said stitching.

ALBERT A. ACKERMAN.
